UNITED STATES PATENT OFFICE.

WANTON D. SLOCUM, OF NEW BEDFORD, MASSACHUSETTS.

NECKBOW-FASTENER.

SPECIFICATION forming part of Letters Patent No. 277,362, dated May 8, 1883.

Application filed January 31, 1883. (No model.)

To all whom it may concern:

Be it known that I, WANTON D. SLOCUM, of New Bedford, in the county of Bristol and State of Massachusetts, have invented a new 5 and useful Improvement in Neckbow-Fasteners, of which the following is a full, clear, and exact description.

Neck ties and bows as used by men and youths have been variously constructed to provide for securing them in place on the person; but the ordinary elastic loop appendage used to attach the bows to the collar-button or stud is both the simplest and neatest fastening for the purpose. There is, however, much difficulty frequently experienced in hanging or putting on the bow with the fingers by its attached elastic loop over said stud or collar-button. To obviate this difficulty is the object of my invention, which consists in a simple 15 instrument of special construction, substantially as hereinafter described for the purpose, and whereby the elastic loop is readily picked up, placed in position over the collar-button or stud, and the bow adjusted with facility to 25 its place.

Reference is to be had to the accompanying drawing, forming part of this specification, in which the figure represents a longitudinal view of a neckbow-fastener constructed in accordance with my invention, and applied, as shown by dotted lines, to a neckbow for placing the same over a collar-button or stud.

The instrument represented in the drawing consists, generally, of a handle, A, and a stock 35 or stem-piece, B, both of which may be made of any suitable material or materials; but it is preferred, for convenience and simplicity, to construct the stem-piece B of wire, which may be doubled and twisted one length around the 40 other for the greater portion of its length, to give it strength as a projection from or exten-

sion of the handle. When the stem B, however, is thus made of wire, its outer end portion should be made of a single thickness, as shown, or such outer end portion may be otherwise constructed, and, if desired, be a separate appendage. Such end portion of the instrument B' forms its loop holder and placer. Said loop holder and placer B' is formed of a rear portion or head, b, spread out laterally in 45 opposite directions, leaving opposite side shoulders, c c, in front, from which a narrow or reduced forward neck portion, d, made to bow inward toward the handle, projects, such curved construction serving to provide for the steady fit of said neck part over the shank portion of the collar-button or stud.

The instrument is used as follows: The neck part d of the loop holder and placer B' is entered within the loop e of the neckbow C, said 50 loop as thus picked up being spread by said part d and resting on the shoulders c c of the head b. The forward portion of said neck part d is then placed over and at the back of the head of the collar-button or stud, and the hand 55 holding the instrument raised to tilt the instrument, so that upon slightly pulling down on the bow the loop e will slip from off the neck part d to its place on and around the shank of the collar-button or stud.

Having thus described my invention, I claim as new and desire to secure by Letters Patent—

A neckbow-fastener consisting of the loop-holder B', having laterally-spread sides b b, neck portion d, and shoulders c c, the said neck 75 portions being adapted to enter the loop to spread the same and secure it to a collar-button, substantially as described.

WANTON D. SLOCUM.
